CLAIM

The ornamental design for a fan heater, as shown and
described.

DESCRIPTION

FIG. 1 is a perspective view of a fan heater showing my
new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and

FIG. 7 is a bottom plan view thereof.

The fragmentary, broken-line showing of an electrical
cord in FIGS. 2, 3, 4, 5 and 7, is for illustrative purposes
only and forms no part of the claimed design.

FIG. 1

FIG. 2

FIG. 3

FIG. 4

FIG. 5

FIG. 6

FIG. 7
